(57) **CLAIM**

The ornamental design for a leash bag, as shown and described.

DESCRIPTION

FIG. 1 is a front perspective view of a leash bag showing our new design.

FIG. 2 is a side elevation of the front side of the leash bag of FIG. 1; and,

FIG. 3 is a side elevation of the back side of the leash bag as viewed from the opposite direction in FIG. 2.

The broken line showing of environmental structure is for illustrative purposes only and forms no part of the claimed design.
